UNITED STATES PATENT OFFICE.

WARREN J. BELCHER, OF HARTFORD, CONNECTICUT, ASSIGNOR TO THE WHITNEY MFG. CO., OF HARTFORD, CONNECTICUT, A CORPORATION OF CONNECTICUT.

METHOD AND APPARATUS FOR FORMING HEADS ON RIVETS.

Application filed December 20, 1923. Serial No. 681,712.

My invention relates to the method and apparatus for forming heads on rivets and is particularly applicable to the formation of heads on pintles as used in chains of the 5 silent link type.

My invention will be better understood by reading the following description taken in connection with the accompanying drawing forming a part thereof and, in which, Fig. 10 1 shows, in front elevation, an apparatus for carrying out my method; Fig. 2 shows another view of the apparatus disclosed in Fig. 1; and Figs. 3 and 4 show details of the riveting element. Fig. 5 shows an end 15 view of the riveted pinte.

In certain types of chains it is necessary to make the pintles of very hard metal so as to reduce the wear and increase the life of the chain. The most satisfactory and economical method of fastening the pintles in 20 the links is to form a rivet-head on the ends of the pintles after the chain is assembled. In the type of chain where a soft pinte may be used the formation of the rivet-head on 25 the end of the pinte presents no particularly difficult problem, but where hard pintles are used, it is a difficult problem to form the rivet-heads on the ends of the pintles. This method, however, may be found advanta- 30 geous with pintles which are not hard in the sense used in the preceding sentence.

Several schemes have been used heretofore; among them the use of electricity to 35 heat the pinte and some suitable means for forming the head while hot; emery discs have been used to raise the temperature of the ends of the pintles by friction and some suitable means subsequently used to form the rivet-heads, and grooves have been 40 placed around the ends of the pintles and snap-collars or washers placed on the ends of the pintles to hold the parts together.

All of the foregoing are objectionable for 45 one reason or another. The electrical heating arrangement is complicated and difficult to operate and is also expensive. It is also impractical if not impossible to sufficiently localize the heating to avoid damage to the hard pintles. The use of the emery wheel 50 has the disadvantage that emery dust gets into the joints of the chain and has a very detrimental effect upon the life of the chain for obvious reasons. The use of grooves and 55 collars is expensive in that it requires a great amount of manual operation.

In my method the pintles, when in position in the chain, may be moved over a supporting sprocket 1, so arranged that one end of the pinte bears against an anvil 2 and the other end of the pinte comes opposite 60 the face of the member 3 which is carried by a holder 4. The holder 4 is mounted in a spindle connected with the pulley 5 and rotated by a belt 6 or other suitable means. The anvil 2 is supported in guides 7 on the 65 base 8 of the machine. The spindle carrying the holder 4 is likewise mounted in guides carried by the base 8. The holder 4 and anvil 2 may be made to approach or recede from each other by any suitable 70 means known in the art. Ordinarily, the anvil 2 does not rotate but, if desired, a holder like the holder 4 may be provided in place of the anvil 2, and rotated. In this instance a member corresponding to the 75 member 3 will be carried by the holder.

The sprocket 1 may be automatically rotated or the chain 9 may be fed through the machine by hand.

A clamping member 10 engages the top of 80 the chain as it comes over the sprocket 1 and holds the chain in position. The chain is fed to the sprocket from a table 11 and after passing over the sprocket and having the rivet-heads formed on the pintles the 85 chain drops into a coil on the floor or on suitable mechanism for transporting it.

As the chain passes through the machine 90 as above described, one end of the pinte rests against the anvil 2 and the other end is opposite the member 3 which is rotating at a high speed. By operating the mechanism provided for that purpose, the anvil 2 and member 3 approach each other and the friction created by the relative movement 95 between the end of the pinte and the member 3 quickly heats the end of the pinte to a high temperature. The heating is effected so quickly that the high temperature does not extend to any substantial extent along 100 the pinte, but remains localized on the end. The temperature is such as to draw the temper- 105 ature from the end of the pinte, and the pressure is such as to cause the metal to flow transversely of the pinte to form the rivet- 110 head 12 on the end of the pinte. This operation of heating and forming the head on the pinte is done very quickly and preferably in one operation, thus entirely avoiding the 115 difficulties mentioned in connection with the

prior methods and, at the same time, producing better results at a greater rate of speed and at very much less expense.

I have discovered that a metal known as 5 stellite is particularly well suited for use in the above method in creating the temperature and forming the heads on the pintles. This metal is very hard and durable and does not lose its hardness perceptibly at the 10 temperatures required in forming the heads on the pintles. It therefore is not substantially worn away by its use as above described. Nor does it take away any substantial amount of the pintle or other member. Stellite has an extremely hard surface which extends to a thickness of possibly a sixty-fourth of an inch. By forming the member 3 in the form of a cube, six surfaces are available and when one of such 20 surfaces is worn away partially, another face of the cube may be presented, and so on, until all six faces of the cube have been used.

In practice I have found that one face of 25 a cube of stellite can be used to place a large number of heads on hard pintles. The cube 3 of stellite is held in place in the holder 4 by the set-screws 13.

The machine may be adjusted for chains 30 of different widths by the hand wheels 14 which move the carriages 15 on the base 8 of the machine.

In some instances I have found it advantageous to place a cube of stellite where 35 the anvil 2 appears in the drawings and to rotate both cubes of stellite and thereby form heads on both ends of the pintles at the same time. Both forms come within the scope of my invention.

40 In the foregoing description and in the appended claims I have used the term "rivet-head" in a broad sense. I do not intend to limit my invention to use on rivets, but intend that it be considered broad 45 enough to include all problems similar to that of forming rivet-heads.

While I have shown and described one form of apparatus for carrying out my method, it will be evident that other forms 50 of apparatus may be used, if desired.

I claim:

1. The method of forming rivet-heads on hard metal members which consists in causing relative rotative movement between the 55 members and a harder surface until the ends of the members are brought to a riveting temperature and the temper drawn locally and creating a pressure between said members and said surface to cause the metal at 60 the ends of the members to flow transversely of the members to form rivet-heads.

2. The method of forming rivet-heads on chain pintles which consists in passing the ends of the pintles into contact with a rotating, non-cutting element, raising the temperature of the ends of the pintles by friction thereby drawing the temper of the metal locally and applying pressure to the heated metal to cause the metal of the pintles to flow to form the rivet-heads.

3. The method of forming heads on rivets which consists in raising the temperature and drawing the temper of the ends of the rivets by friction and simultaneously applying pressure to the heated ends to form 75 the heads.

4. The method of forming heads on rivets which consists in raising the temperature and drawing the temper of the ends of the rivets by friction by a non-cutting surface and applying pressure to the heated ends through the friction means to form heads on the rivets.

5. The method of forming heads on rivets of hard metal which consists in pressing a 85 non-cutting, rotating surface to the end of the rivet to raise the temperature and draw the temper of the end of the rivet and cause the metal to flow to form the head.

6. The method of forming heads on rivets of hard metal which consists in pressing a 90 rotating surface of stellite to the end of the rivet to raise the temperature of the end of the rivet and cause the metal to flow to form the head.

7. The method of forming rivet-heads on chain pintles which consists in passing both 95 ends of the pintles into contact with rotating, non-cutting elements, raising the temperature and drawing the temper of the ends of the pintles by friction and applying pressure to the heated metal to cause the metal of the pintles to flow to form rivet-heads.

8. The method of forming heads on hard 100 pintles for chains which consists in frictionally heating and drawing the temper of the ends of the pintles for a distance not substantially beyond the head to be formed and applying pressure by the frictional heating means to the heated portion to form the head without substantial loss of metal from the pintle.

9. The method of forming heads on hard 105 metal pintles for chains which consists in placing the pintles in the links of the chain, drawing the temper locally of the ends of the pintles by frictional heat and applying pressure by the heating means to the heated 110 area to form the heads without substantial loss of metal from the pintle.

WARREN J. BELCHER.
